UNITED STATES PATENT OFFICE.

LILLIAN GOODMAN, OF NEW YORK, N. Y., ASSIGNOR TO WOOL NOVELTY CO., INC., OF NEW YORK, N. Y., A CORPORATION OF NEW YORK.

DESIGN FOR A BIFURCATED GARMENT.

60,787.

Specification for Design.

Patented Apr. 11, 1922.

Application filed September 22, 1921. Serial No. 502,578. Term of patent 7 years.

To all whom it may concern:

Be it known that I, LILLIAN GOODMAN, a citizen of Russia, and a resident of the borough of Manhattan, city, county, and State of New York, have invented a new, original, and ornamental Design for Convertible Bifurcated Garments, of which the following description, in connection with the accompanying drawing, is a specification.

The single figure of the drawing is a perspective view of a bifurcated garment, showing my design.

I claim as my invention:

The ornamental design for a bifurcated garment, as shown.

LILLIAN GOODMAN.
